(57) **CLAIM**

The ornamental design for a fluid controller, as shown and described.

DESCRIPTION

FIG. 1 is a top and right front perspective view of a fluid controller, showing our design;

FIG. 2 is a front elevational view thereof, with a rear elevational view being a mirror image thereof;

FIG. 3 is a top plan view thereof, showing cross-sectional reference lines 8-8 for FIG. 8;

FIG. 4 is a bottom elevational view thereof;

FIG. 5 is a right side elevational view thereof, with a left side elevational view being a mirror image thereof; and

FIG. 6 is a right side elevational view thereof, showing cross-sectional reference lines 7-7 for FIG. 7;

FIG. 7 is a partial cross-sectional view thereof along lines 7-7 shown in FIG. 6;

FIG. 8 is a cross-sectional view thereof along lines 8-8 shown in FIG. 3; and,

FIG. 9 is a top plan view thereof, showing a handle in a rotated orientation.
